UNITED STATES PATENT OFFICE.

DUNCAN STEWART, OF GLASGOW, COUNTY OF LANARK, SCOTLAND.

MACHINE FOR BEETLING CLOTH.

SPECIFICATION forming part of Letters Patent No. 387,749, dated August 14, 1883.

Application filed December 11, 1883. Serial No. 114,927. (No model.) Patented in England August 10, 1881, No. 3,462.

To all whom it may concern:

Be it known that I, DUNCAN STEWART, a subject of the Queen of Great Britain and Ireland, residing at Glasgow, in the county of 5 Lanark, Scotland, have invented certain Improvements in Machines for Beetling Cloth, (for which I have obtained a patent in Great Britain, dated August 10, 1881, No. 3,462,) of which the following is a specification.

10 My invention consists of an improved machine for the beetling, calendering, or finishing of woven fabrics, felt, paper, or yarn, as hereinafter described.

For the better understanding of the manner 15 of using my improved machine, I have shown in the accompanying drawings, and have hereinafter described, a number of accompanying devices which do not form any essential part of my present invention, for the latter relates 20 only to the construction of the rotary beetling-cylinder itself.

Figure 1 on the accompanying sheet of drawings is a plan of the machinery, and Fig. 2 is a corresponding sectional elevation. Figs. 3 25 and 4 are enlarged sectional views of two modifications of the spring-beetler.

My improved beetler is a shaft, 5, having 30 on it a number of bands, 6, made of steel or other suitable elastic metal, bent each, as shown in Fig. 3, into a spiral (volute-shaped) coil, or in an analogous manner, as shown in Fig. 4. The bands or coils 6 are fixed to the shaft 5 by means of their inner ends, on which ends dovetail pieces are formed or welded, to 35 be fastened by keys in dovetail sockets formed for them on a boss, 7, keyed on the shaft. The outer ends of the bands or coils 6 are free to move to a certain extent, and have rounded striking-pieces 8 formed or welded or otherwise fixed on them, and they are prevented 40 from flying out too far through centrifugal action when rotating by stop-pins 9, fixed in disks or projecting plates 9', formed or fixed on the boss 7, these pins 9 acting on the extreme ends of the bands, as shown in Fig. 3, 45 or on loops, as shown in Fig. 4. The bands 6 are placed on the shaft 5, so that their several ends are at different parts of the circle, and the shaft being made to rotate at a considerable speed in the direction of the arrows, 50 the ends of the bands tend to fly out by cen-

trifugal action, and in passing round strike the goods which are subjected to them. The goods pass round a roller, 10, placed parallel to the beetler-shaft 5.

55 The beetler bands or springs 6 may be from two to four inches broad.

The action of the beetler is capable of being varied through a considerable range by varying the speed of rotation and the distance between the beetler-shaft 5 and the roller 10, on which the goods are supported while being operated on.

60 The beetler-shaft 5 and the roller 10 may be mounted and driven in the manner shown in the drawings. The parts are carried on a framing consisting of a pair of parallel side frames, 11, bolted down to a suitable foundation and connected by tie-rods 32, Figs. 1 and 2.

65 The beetler-shaft 5 is held in bearing-blocks 12, which are adjustable horizontally on the tops of the frames 11. The adjustment of both bearing-blocks 12 is effected simultaneously by means of a hand-wheel, 13, on a small horizontal shaft, 14, having on it worms 13' in gear 75 with worm-wheels 14' on screw-spindles 15, which act on the bearing-blocks. A guard, 16, (not shown in Fig. 1,) is placed over the beetler-bands 6, to prevent anything from getting improperly into contact with them.

80 The beetler-shaft 5 has on one end of it fast and loose pulleys 17, for a driving-belt from an overhead shaft, and on the other end of it there is a pulley, 18, for a belt for driving a shaft, 19, below. A worm, 19', Fig. 1, on the low shaft 19, gears with a worm-wheel, 20, on a vertical shaft, 21, which, by means of bevel-wheels 22, drives the roller 10, round which the fabrics pass while being acted on by the beetler. The low shaft 19 has also on it a small pulley, 23', for a belt, 23, which drives a grooved roller, 24. The grooves are arranged spirally and run in opposite directions from the center, so that as the roller turns it has the effect of breadthening or smoothing out the 95 fabric as it is going upon the roller 10.

90 The fabric to be operated on passes round two other rollers, 25 26, besides the one 10 which presents it to the action of the beetler, the three rollers being at the angles of the triangle 100 arranged so that the fabric incloses a space, 27, descending from the roller 10 to a roller,

25, beneath the flooring 33, thence proceeding vertically upward to the third roller, 26, and returning downward again to the roller 10. The fabric is first entered from the in-
5 closed space 27, and passing beneath breadth-
ener-bars 28 and in contact with the breadth-
ener-roller 24, hereinbefore referred to, pro-
ceeds round the outer side of the roller 10. The
fabric is led round the three rollers 10, 25,
10 and 26 two, three, or more times, so as to form
as many plies or thicknesses on the roller 10,
each part being in this way operated on sev-
eral times, each time with fewer thicknesses
outside of it, and receiving the final action of
15 the beetler directly on it while having other
thicknesses acting as a cushion under it. The
fabric finally passes round a guide-roller, 29,
to swinging folding mechanism 30, of a well-
known kind, which deposits it in a folded
20 pile, 31.

In the drawings I have shown the folding

mechanism as consisting of a pendent swing-
ing frame, 34, carrying at its lower end guide-
rollers 35 for the fabric, and being connected
at its upper end by a rod or rods, 36, to a crank 25
or cranks, 37, on the driving-shaft 38, which
imparts a vibrating motion to the frame to
fold the cloth back and forth in layers.

I claim as my invention—

The rotating spring-beetler consisting of a 30
shaft carrying elastic metal bands bent into
coiled or similar form, and disks or plates car-
rying stops for the outer ends of the bent bands,
substantially as set forth.

In testimony whereof I have signed my name 35
to this specification in the presence of two sub-
scribing witnesses.

DUNCAN STEWART.
